Jessie R. Matthews and William A. Davidson,
Norfolk, Va., assignors of seventeen one-
hundredths to P. H. Mason, seventeen one-
hundredths to W. D. Mason, and seventeen one-
hundredths to J. H. Mason, all of Norfolk, Va.

Application March 29, 1945, Serial No. 118,766

Term of patent 3½ years

(Cl. D64—10)

To all whom it may concern:

Be it known that we, Jessie R. Matthews and William A. Davidson, citizens of the United States, residing at Norfolk, in the county of Norfolk and State of Virginia, have invented a new, original, and ornamental Design for Corner Marker, of which the following is a specification, reference being had to the accompanying drawings, forming part thereof.

Figure 1 is a bottom perspective view of a corner marker showing our new design;

Figure 2 is a top perspective view thereof;
Figure 3 is a bottom plan view thereof;
Figure 4 is a top plan view thereof;
Figure 5 is a side elevational view thereof; and
Figure 6 is a side elevational view at right angles to Figure 5.

We claim:

The ornamental design for a corner marker, as shown.

JESSIE R. MATTHEWS.
WILLIAM A. DAVIDSON.
